CLAUDE DE F. SMITH, OF NEW YORK, N. Y., ASSIGNOR TO SMITH SIGNAL CORPORATION, OF NEW YORK, N. Y., A CORPORATION OF DELAWARE.

THREE-WAY SWITCH.

1,389,848.

Specification of Letters Patent. Patented Sept. 6, 1921.

Application filed January 24, 1920. Serial No. 353,722.

To all whom it may concern:

Be it known that I, CLAUDE DE F. SMITH, a citizen of the United States, and resident of the borough of Manhattan, in the city, 5 county, and State of New York, have invented a new and useful Three-Way Switch, of which the following is a specification.

The invention relates to three-way switches suitable particularly for automobile rear-end signals, and comprises certain features of construction and combination, the general purpose of which is the production of a device having great convenience and certainty of operation, with simplicity 15 and compactness. A preferred embodiment of the invention is illustrated in the drawings and described hereinafter, and the matters of novelty are more particularly pointed out in the appended claims.

20 In the accompanying drawings forming a part hereof:

Figure 1 is a plan or face view of the switch with the cover off, the blade being shown in neutral position in full lines, and 25 swung to one of its lateral circuit-closing positions, in dotted lines;

Fig. 2 is a section on the line 2—2 of Fig. 1, with the cover on, the entire blade being shown in elevation, pulled forward to another of its circuit-closing positions;

Fig. 3 is a view looking at the rear edge of Fig. 1;

Fig. 4 is a fragmentary face view of the base and parts thereon, with the common 35 bridging contact and the blade removed;

Fig. 5 is an enlarged fragmentary side view showing a wing of the blade entered between a pair of stationary contacts in one of the lateral positions of the blade;

40 Fig. 6 is a perspective view of the blade; and

Figs. 7 and 8 are side and perspective views of a locking washer.

The switch has a flat base 1 of insulation, 45 and a cover 2 fastened by screws 3.

A flat blade 4 lies over and slightly spaced from the base, projecting outwardly therefrom at the front, where it bears a handle knob 5. An upwardly projecting pivot post 6 is secured in the base, approximately at the center, and passes through a longitudinal slot 7 in the blade. The slotted portion of the blade rests upon a shoulder 8 of the pivot above the surface of the base, and is held

55 closely thereto by a washer 9, a nut 10 on the top of the pivot, and a spring 11 interposed between the nut and washer. The washer is made with downturned ears 12, which embrace the blade, to hold the two against turning relatively to each other, and 60 with low, rounded, downwardly projecting protuberances 13 at the sides of its central opening. Said protuberances are coöperative with notches 13^a in the upper face of the blade adjacent the front and rear ends 65 of the slotted region, whereby an impositive or yielding lock is formed to hold the blade in either of two positions, with reference to longitudinal movement.

Forwardly of the pivot, near the front of 70 the base, the blade rests frictionally upon a curved plate 14, which constitutes a keeper, and in the illustrated construction also serves as a current-receiving contact. The body of this plate is raised somewhat above the 75 base, by virtue of its ends being offset downwardly, said ends being secured to the base by screws 15, one of which serves as a binding post to hold a battery wire 16. The blade is held frictionally to the keeper by 80 means of a resilient tongue 17 riveted to the blade behind the handle 5 and extending rearward beneath the raised body of the plate. A longitudinally arranged pair of rounded protuberances 18 struck down from 85 the portion of the blade which rides on the keeper coöperate with corresponding pairs of notches 19 in the plate, at the center and adjacent the two ends.

It will thus be seen that the blade has a 90 longitudinally sliding and pivotal mounting, whereby it can be swung laterally to either side of neutral, or pulled forwardly and pushed back, and that impositive locking means are provided whereby the blade is 95 held in either of two positions with respect to longitudinal movement, and any one of three positions as to lateral movement. The normal or neutral position of the blade is 100 central and rearward. The extent of longitudinal movement is limited by the length of the slot 7, and the extent of swinging movement by the tongue 17 striking against the shoulders 20 toward the ends of the plate 14.

105 Two contacts 21, 22, which will be termed for convenience right and left contacts, are fastened to the base at opposite sides by

screws 23, which serve to bind the wires 24, 25 of two of the external circuits controlled by the switch. Said contacts may be in the form of strips extending forwardly from 5 the screws and having their forward portions offset upwardly and bent downwardly at the ends, to form spring-yielding tongues. These contacts are engaged by oppositely projecting lateral wings 26, 27 on the blade, 10 positioned so that when the blade is rearward and swung to right or left one of the wings rides frictionally upon the corresponding spring-yielding contact tongue.

A third contact is formed by a plate 28 15 secured to the base behind the pivot by screws 29, to one of which the wire 30 of a third external circuit is secured. This contact is beneath the blade and spaced therefrom. A downwardly bent spring 20 tongue or lower face projection 31 on the rear end of the blade clears the contact in the neutral position, and also in the right and left positions of the blade, when the latter is rearward, but rides upon the contact when the blade is pulled forward. The contact 28 is made curved and long enough 25 to be engaged by the projection 31, whether the blade is central or at the right or left provided it is pulled out, and when the blade 30 is out its wings 26, 27 are displaced with reference to the right and left contacts 21, 22 so that they cannot engage therewith. Thus, it is not necessary to pass to central 35 in order to break the right or left circuit and close the third circuit, or vice versa. That is to say, for example, if the blade is at the right, closed on contact 21, the circuits of contacts 22 and 28 being open, the circuit of contact 21 can be opened and the 40 blade closed on contact 28 simply by drawing it forward without changing its angular position.

A common contact member 32 is arranged 45 so as to be clear of the blade in neutral position and to be electrically engaged thereby in any of the positions of the latter in which it is closed upon the contacts 21, 22 or 28. Said member preferably consists of a bridge 50 passing freely over the rear portion of the blade, in all rearward positions of the latter, the ends of the bridge being offset downwardly and fastened to the base by screws 33. Toward the ends of the bridge are forwardly projecting contact portions or 55 tongues 34, 35, over and opposite the tongues of the right and left contacts 21, 22, and formed similarly and reversely thereto, that is to say offset downwardly and having their extremities curved up. The two pairs of 60 tongues thus form spring sockets in which the wings 26, 27 are frictionally received when the blade is swung right or left in the rearward condition. Thereby electrical connection is made simultaneously from the 65 blade to the contact 21 and the common con-

tact member, or to the contact 22 and the common contact member, as the case may be.

The intermediate portion of the bridge is curved rearward behind the pivot and lies over the contact 28, and the rear end of the 70 blade is formed with another tongue 36, offset upwardly, forming an upper face projection, which when the blade is moved forward rides beneath said intermediate portion of the bridge, at the same time that 75 the tongue 31 rides upon the contact 28. The bridge yielding resiliently at such time insures a good contact. The arrangement of the contact 28, bridge 32 and face projections 31 and 36 is such, it will be noted, 80 that connection is established from the blade to the bridge or common contact member whenever the blade is closed upon the contact 28, that is to say whenever the blade is forward, whether in central or laterally 85 displaced position.

The common contact member is utilized to cause the sounding of a buzzer or self-contained signal 37, which in the construction illustrated is secured beneath the top 90 of the cover 2 and connected with the bridge by a wire 38 passing to one of the screws 33. Another wire 39 from the buzzer leads to ground or back to the battery. The buzzer will therefore be sounded whenever an 95 external circuit is made through any one of the three contacts 21, 22, 28, and its failure to sound when the blade is moved to any of its operative positions will indicate something wrong in the switch or in the circuits 100 or apparatus controlled thereby.

From the foregoing it will be understood that with the switch blade central and to the rear, current is on the blade through the plate 14, but all three external circuits and 105 the buzzer circuit are open. If the blade is swung to the right, while remaining rearward, it closes a circuit through the right contact 21 and also closes the buzzer circuit, by reason of the wing 26 passing frictionally between said contact and the contact 110 tongue 34 of the member 32. Similarly, if the blade is swung to the left, wing 27 passes frictionally between left contact 22 and contact tongue 35 of the bridge, thus closing 115 the left circuit and the buzzer circuit. Finally, if the blade be drawn forward the lower and upper face projections 31, 36 engage simultaneously with the third contact 28, closing its circuit, and with the 120 bridge or common contact member, closing the buzzer circuit.

Numerous changes in form, proportions and arrangement may be made without departing from essentials.

What I claim as new is:

1. A three-way switch having a blade provided with a mounting whereby it can be swung laterally and moved longitudinally, right and left stationary contacts engage- 130

- able by swinging, and a third contact engageable by longitudinal movement of the blade, the relations being such that the blade engages the third contact through longitudinal movement irrespective of its position in respect to swinging and when so moved does not engage either of the right and left contacts.
2. A three-way switch having a blade provided with a mounting whereby it can be swung laterally and moved longitudinally, right and left stationary contacts engageable by swinging, a third contact engageable by longitudinal movement of the blade, the relations being such that the blade engages the third contact through longitudinal movement irrespective of its position in respect to swinging and when so moved does not engage either of the right and left contacts, and a common contact from which the blade is disengaged in neutral position and which is adapted to be engaged by the blade whenever the latter engages any one of said three contacts.
3. A three-way switch comprising a base, a blade provided with a longitudinally sliding and pivotal mounting whereby it can be swung laterally and pulled forwardly on the base, right and left contacts with which the blade is alternately engageable by swinging and another contact with which it engages on being pulled out, the blade having oppositely projecting lateral wings adapted to coöperate with the right and left contacts in the rearward condition of the blade only, and a face projection for coöperation with the third contact, said third contact being extended at opposite sides of the central position of the blade, so as to be engageable by the blade irrespective of its angular position.
4. A three-way switch comprising a base, a blade provided with a mounting whereby it can be swung laterally and moved longitudinally on the base, right and left contacts engageable alternately by the blade by swinging, a third contact engageable by the blade on longitudinal movement, and a common contact member from which the blade is disengaged in neutral position and with which it engages simultaneously with each of said other contacts, said common contact member having portions opposite said right and left contacts, between which and said contacts the blade is frictionally received.
5. A three-way switch comprising a base, a blade provided with a mounting whereby it can be swung laterally and moved longitudinally on the base, right and left contacts engageable alternately by the blade by swinging, a third contact engageable by the blade on longitudinal movement, and a common contact member from which the blade is disengaged in neutral position and with which it engages simultaneously with each
- of said other contacts, said common contact member having portions opposite said right and left contacts, and the blade having oppositely projecting lateral wings to enter frictionally between said contacts and contact portions when the blade is swung.
6. A three-way switch comprising a base of insulation, a blade provided with a mounting whereby it can be swung laterally and moved longitudinally on the base, right and left contacts engageable alternately by the blade by swinging, a third contact engageable by the blade on longitudinal movement, and a common contact member bridging the blade from which contact the blade is disengaged in neutral position and with which it engages simultaneously with each of said other contacts, said blade having projections on opposite faces arranged to engage simultaneously with the third contact and with the common contact member when the blade is moved lengthwise.
7. A three-way switch comprising a base, a blade provided with a mounting whereby it can be swung laterally and moved longitudinally on the base, right and left contacts engageable alternately by the blade by swinging, a third contact engageable by the blade on longitudinal movement, and a common contact member from which the blade is disengaged in neutral position and with which it engages simultaneously with each of said other contacts, said common contact member having portions opposite said right and left contacts, and the blade having oppositely projecting lateral wings to enter frictionally between said contacts and contact portions when the blade is swung, and being further provided with projections on opposite faces to engage simultaneously with the third contact and the contact member when the blade is moved lengthwise.
8. A three-way switch comprising a base of insulation, a blade provided with a mounting whereby it can be swung laterally and moved longitudinally on the base, right and left contacts on the base engageable alternately by the blade by swinging, a third contact engageable by moving the blade lengthwise, and a common contact member bridging the blade out of contact therewith in neutral position and arranged to be engaged thereby simultaneously with each of said three contacts.
9. A three-way switch comprising a base, a blade provided with a mounting whereby it can be swung laterally and moved longitudinally on the base, right and left contacts on the base engageable alternately by the blade by swinging, a third contact engageable by moving the blade lengthwise, and a common contact member bridging the blade out of contact therewith in neutral position and arranged to be engaged thereby simultaneously with each of said three contacts,

said bridging contact member having end contact portions opposite the right and left hand contacts.

10. A three-way switch comprising a base, 5 a blade provided with a mounting whereby it can be swung laterally and moved longitudinally on the base, right and left contacts on the base engageable alternately by the blade by swinging, a third contact engageable by moving the blade lengthwise, and a common contact member bridging the blade out of contact therewith in neutral position and arranged to be engaged thereby simultaneously with each of said three contacts, said 15 blade having oppositely projecting lateral blades to enter frictionally between said contacts and contact portions, and face projections adapted to engage with the third contact and the central part of the bridging contact member.

11. A three-way switch comprising a base, a blade provided with a mounting whereby it can be swung laterally and moved longitudinally on the base, right and left contacts, a 25 third contact beneath the blade and normally out of contact therewith, and a common contact member over the blade and normally out of contact therewith and having end contact portions over the right and left 30 contacts, the blade being adapted to pass frictionally between said contacts and contact portions when swung and having upper and lower face projections to engage the third contact member when moved lengthwise.

12. A three-way switch comprising a pivoted and longitudinally sliding blade, two contacts wherewith the blade is alternately engageable by swinging, a third contact engaged by the blade by longitudinal movement, impositive snap holding means at the 35

pivot for holding the blade in respect to longitudinal movement, and means removed from the pivot for holding the blade in its positions of pivotal movement.

13. In a switch of the character described, the combination with a base and a pivot, of a blade having a slot engaging said pivot whereby it can be swung and moved longitudinally, said blade being further provided with impositive holding elements spaced in the longitudinal direction at the region of the slot, and yielding confining means comprising a member on the pivot co-operative with said elements to hold the blade in longitudinally shifted positions.

14. In a switch of the character described, the combination with a base and a pivot, of a blade having a slot engaging said pivot whereby it can be swung and moved longitudinally, said blade being further provided with impositive holding elements spaced in the longitudinal direction at the region of the slot, and yielding confining means comprising a member on the pivot having means 65 engaging the blade so as to turn therewith while permitting the blade to slide and means co-operative with said elements so as to hold the blade in longitudinally shifted positions.

15. In a switch of the character described, the combination with a base and a pivot, of a blade having a slot engaging said pivot whereby it can be swung and moved longitudinally, said blade being further provided with impositive holding elements spaced in 75 the longitudinal direction at the region of the slot, and yielding confining means comprising a member arranged to turn on the pivot and having ears embracing the blade and a holding element to engage alternately 80 with the holding elements of the blade.

CLAUDE DE F. SMITH.
